UNITED STATES PATENT OFFICE.

EMIL P. STARY, OF CEDAR RAPIDS, IOWA.

AUTOMATIC FLUSHING-TANK.

1,190,604.

Specification of Letters Patent. Patented July 11, 1916.

Application filed August 31, 1912. Serial No. 718,140.

To all whom it may concern:

Be it known that I, EMIL P. STARY, a citizen of the United States, residing at Cedar Rapids, in the county of Linn and State of 5 Iowa, have invented a new and useful Automatic Flushing-Tank, of which the following is a specification.

This invention relates to automatic flushing tanks and is more particularly an improvement upon the structure disclosed in 10 Patent No. 969,305, issued to me on September 6, 1910.

One of the objects of the invention is to provide simple and efficient means whereby 15 the liquid contents of a tank or reservoir can be automatically and intermittently discharged and which is devoid of movable parts which might get out of order.

Another object is to provide improved 20 means for controlling the operation of the siphon.

With the foregoing and other objects in view which will appear as the description proceeds, the invention resides in the combination and arrangement of parts and in the details of construction hereinafter described 25 and claimed, it being understood that changes in the precise embodiment of the invention herein disclosed, can be made within 30 the scope of what is claimed, without departing from the spirit of the invention.

In the accompanying drawings the preferred form of the invention has been shown.

In said drawings: Figure 1 is a section 35 through a tank having the present improvements combined therewith. Fig. 2 is a plan view of the structure shown in Fig. 1. Fig. 3 is a section on line A—B Fig. 1.

Referring to the figures by characters of 40 reference 1 designates a tank or reservoir of any desired form and size and the same has a valved inlet 2, while extending from the bottom of the tank is an outlet pipe 3 or the like.

45 The structure constituting the present invention includes a container 4 which is preferably cylindrical and which is overhung by a bell 5 concentric therewith and spaced therefrom. An inner bell 6 extends downwardly into the container 4 and projecting into the inner bell to a point below the upper edge of the container 4 is a discharge pipe 7 the lower end of which fits into the outlet opening 8 in the bottom of the container 4 and from which the pipe 3 extends. An air

pipe 9 extends downwardly along the outer face of the inner bell 6 and thence upwardly along the inner face thereof, the inner end of the pipe 9 being located in a lower plane than the outer end of the pipe, as will be 60 clearly apparent by referring to Fig. 1. The outer end of pipe 9 is located above the plane occupied by the upper edge of the container 4. Pipe 7, bells 5 and 6 and the container 4 are all preferably concentric. 65

In using the apparatus the container 4 and the air pipe 9 are filled with liquid. Liquid is then discharged into the tank or reservoir and when it reaches a predetermined depth, the pressure of the liquid becomes such as to force the confined air out of the bell 5 through the pipe 9. Thus a flow of liquid will be set up through bell 5, pipe 9 and bell 6 to the pipe 7 whereupon siphonic action will take place until the level 70 of the water comes to a point slightly below the lower edge of the bell 5 whereupon the siphonic action is broken and the discharge of liquid ceases leaving sufficient liquid in the container 4 and the air pipe 9 for the 80 next operation. The level of the liquid discharged into the tank 1 from the pipe 2 again rises as before whereupon the operation described will be repeated.

By referring to Fig. 1 it will be seen that 85 the pipe 7 is provided with an interiorly reduced portion 7^a. This is advantageous for the reason that, as the liquid in the tank begins to discharge downwardly through the pipe 7, it will strike the reduced portion and rebound inwardly, thus quickly choking the outlet portion of the pipe 7 and more quickly setting up the siphonic action than would be the case should the interior of the pipe 7 be of uniform diameter throughout 95 the length thereof.

What is claimed is:—

The combination with a receptacle having means for continuously supplying fluid thereto, of an outlet pipe extending from the bottom of the receptacle, a container resting upon the bottom of the receptacle and concentric with the outlet, a pipe within the container and extending through the bottom thereof and into the outlet, that portion of 100 said pipe within the outlet being frustoconical to constitute fluid deflecting means, outer and inner bells within the receptacle, said container being extended between the 105 bells and the inner bell extending below the 110

outer bell, and a U-shaped air conductor integral with the inner bell and extending along the inner and outer faces thereof and under said inner bell, both ends of said conductor being extended above the container and the outlet pipe, the outer end of the conductor being above the inner end thereof.

In testimony that I claim the foregoing as my own, I have hereto affixed my signature in the presence of two witnesses.

EMIL P. STARY.
